STEAM BOILER

Karl C. Schmidt, Western Springs, Ill., assignor
to The Babcock & Wilcox Company, Newark,
N. J., a corporation of New Jersey

Application September 25, 1936, Serial No. 102,492

11 Claims. (Cl. 122—336)

My present invention relates to the construction and operation of steam boilers of the water tube type and more particularly to steam boilers adapted for installations having limited head room and floor space available. In my prior application, Serial No. 16,115, filed April 13, 1935, a steam boiler adapted for such use is disclosed having a relatively large amount of convection and radiant heat absorbing surface, furnace volume, and length of heating gas travel in proportion to the space occupied and head room required.

The main object of my present invention is the provision of an improved furnace construction for a steam boiler of the general type described in my prior application for adapting the same for stoker firing at relatively high efficiencies. A further object is the provision of means for effecting an improved flow of heating gases over the convection heating surface.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

Of the drawings:

Fig. 1 is a transverse vertical section of a steam boiler constructed in accordance with my invention taken on the line 1—1 of Fig. 2;

Fig. 2 is a longitudinal vertical section taken on the line 2—2 of Fig. 1;

Fig. 3 is a horizontal section taken on the line 3—3 of Fig. 2;

Fig. 4 is a view similar to Fig. 2 of a modified construction;

Fig. 5 is a view similar to Fig. 3 of the modification shown in Fig. 4;

Fig. 6 is a view similar to Fig. 1 of the modification shown in Figs. 4 and 5; and

Fig. 7 is a view similar to Fig. 6 of a second modification.

The steam boiler unit illustrated in Figs. 1 to 3 comprises a setting or housing substantially rectangular in horizontal and vertical cross sections, and formed by a vertical front wall 10, rear wall 11, side walls 12 and 13, inclined top wall or roof 14, and bottom wall or floor 15. The vertical walls of the setting are formed in general by an outer steel casing 16, a layer of 55 insulating material 17, and a refractory lining

18. The side wall 12 preferably includes hollow tile 12^a arranged to form air passages open at their lower ends. Extending upwardly along the opposite side walls are structural steel columns 19 which support girders 20 extending across and 5 above the top of the setting.

The interior of the setting is divided as hereinafter described into a relatively wide combustion lane or furnace chamber 21 and a relatively narrow laterally adjoining heating lane or tube 10 chamber 22. A pair of longitudinally disposed parallel upper and lower drums 23 and 24 respectively extend longitudinally and throughout the length of the heating lane and are connected throughout their length by a bank of vertically 15 disposed tubes 25 straight for most of their length and having bent ends for radial connection into the drums at both sides of the central vertical planes thereof. The upper or steam and water drum 23 is inwardly offset slightly from the lower 20 or water drum 24. The upper drum 23 is supported from the structural steel members 20, indicated in Fig. 1 as carried by the members 19, and in turn supports the lower drum 24 through the tube bank 25.

The heating lane 22 is separated from the adjoining combustion lane 21 except at the rear end thereof by a vertically disposed refractory partition 26 which extends between the drums and terminates at its rear end a substantial distance 30 from the rear wall 11. The lower drum is adequately protected along its inner side by a refractory curb 27 on the floor 15 and by the thickened lower section of the partition 26. The spaces between the outer side of the drums 23 and 24 and the side wall 13 are closed by refractory material so that heating gases entering the rear end of the heating lane will be confined in the space therein between the drums. A heating gas outlet or stack connection 28 controlled by 40 a damper 29 is provided at the front end of the heating lane. With this arrangement heating gases generated in the combustion lane will flow longitudinally thereof, entering the rear end of the heating lane and passing forwardly therein 45 to the stack connection 28.

The steam boiler illustrated is especially designed for the burning of solid fuel in a bed in the forward end of the combustion lane. A single retort underfeeder stoker 30 is conventionally illustrated in the forward half of the combustion lane. The stoker is mounted on laterally spaced walls 31 defining the sides of an air-chamber 32 which is supplied by an external forced draft fan 33. Solid fuel from a magazine 34 is fed by a 55

suitable feeding mechanism 35 into the stoker retort 36 from which it is forced outwardly over the stoker grates 37. Dumping grates 38 along the sides of the stoker permit the fuel residue to be dropped into ash pits 39 along the sides of the air chamber 32 and from which it is removed through suitable cleanout doors in the lower part of the front wall 10.

The gas flow area of the combustion lane is substantially restricted at the rear end of the stoker by a transverse refractory dividing structure 40 formed by a bridge wall 41, wing walls 42, and an arch 43, which unite to define a restricted throat or gas outlet 44 between the front and rear sections of the combustion lane. With this structure the combustible gas from the fuel bed and air as yet uncombined will be intimately mixed by the high degree of turbulence on passing through the throat into the rear section of the combustion lane and complete combustion in the combustion lane will be insured.

This throat divides the combustion lane into two parts, a forward part having the bed of solid fuel with which the air reacts to form complete and incomplete gaseous products of combustion with excess air, and a rearward part in which the combustible gas combines with some of the excess air. The first stage of combustion in which the solid fuel reacts with air to form gaseous products requires a temperature as high as possible consistent with ash clinkering limits, and the correct temperature is assured by a suitable ratio of hot to cold portions of its boundary walls. The second stage of combustion in which the last traces of combustible gas are burned in as little excess air as possible may be advantageously carried out within walls that have a larger ratio of cold to hot boundary wall surface and the throat divides this section from the forward one.

A relatively large proportion of the heating surface of the unit is formed by tubes receiving radiant heat from the combustion lane. In the stoker section in front of the throat a row of tubes 50 extends upwardly from the drum 24 at the combustion lane side of the partition 26. Spaced tubes 50^a are connected directly to the upper drum 23, while the intermediate tubes 50^b are L-shaped and have outwardly inclined legs 50^c extending across the upper part of the combustion lane to a header 51 at the junction of the side wall 12 and top wall 14. The header 51 extends the full length of the unit and is advantageously supported by longitudinally spaced hangers 52 from the structural steel members 20. The header 51 is connected to the upper drum 23 by a row of roof tubes 53, which as shown, correspond in number to the tubes 50^a and 50^b.

The outer side wall 12 of the stoker section is made of refractory with its outer face air cooled by the hollow tile ducts 12^a. By proper selection of the spacing of the water tubes 50 on one side wall, the tubes 50^c over the furnace and 53 along the roof, and of the area of the outer side and front walls, the temperature of the stoker section in front of the throat may be made as high as desirable.

At the rear side of the throat the header 51 is connected to the lower drum by L-shaped tubes 54 having outwardly inclined legs extending across the lower part of the combustion lane above the floor thereof and vertical legs extending along the outer side wall 12. Roof tubes 53 connect the rear portion of the header to the upper drum. A cleanout door 55 is provided in

the rear wall 11 for removing ash deposited on the floor of the combustion lane rear section. The ash deposited on this floor is protected against fusion by the horizontal legs of the tubes 54 spaced above the floor. There are spaced 5 water tubes on both sides above and below the gases in this section of the combustion lane rearward of the throat, and the ratio of cold to hot area is larger than in the section forward of the throat, and the value of the ratio may be selected 10 by the spacing of the enclosing tubes.

The inner side of the rear section of the combustion lane is defined by a rear section 26^a of the partition 26 which extends rearwardly from the inner wing wall 42 at a point offset towards 15 the side wall 12. Additional rows of water tubes 25^a are provided in the rear section at opposite sides of the partition section 26^a. These rows of tubes extend beyond the rear end of the partition section and form a screen across the entrance 20 to the heating lane. The heating lane side of the inner wing wall 42 and partition is cut away at an angle as indicated at 56 to facilitate gas flow from the wide to the narrow part of the forwardly tapering heating lane. This construction substantially contributes to the maintenance of a higher heat transfer rate as the gases become cooler by increasing the mass velocity toward the outlet of the heating lane.

With the described construction and arrangement, fuel is automatically delivered to and burned on the stoker at a rate suitable for the load and air supplied by the forced draft fan. The gases generated flow rearwardly through the throat 44 into the rear section where combustion 35 is completed. The products of complete combustion or heating gases pass around the rear end of the partition section 26^a and forwardly through the heating lane at a substantially increasing mass velocity to the stack connection 28. To 40 avoid by-passing of the lower portions of the water tubes at the front end of the heating lane, baffle means are installed in that portion of the heating lane to cause the heating gases to pass downwardly before leaving the heating lane. As 45 shown in Figs. 1 and 3, a two-section baffle is used having a stationary upper section 60 and a vertically adjustable lower section 61. The lower section is carried by a guided rack 62 which can be raised or lowered by a pinion 63 on a manually 50 operable shaft 64.

Feed water is supplied to the front end of the upper drum or at any other suitable point and flows downwardly through the forward portion of the tube bank to the lower drum. Most of the 55 steam is generated in the tubes receiving radiant heat from the combustion lane and in the tubes in the rear portion of the heating lane. A steam outlet 65 is indicated at the forward end of the upper drum.

In the modification shown in Figs. 4 to 6, the furnace chamber 21 and heating lane 22 are transposed so that the tube bank 25 is at the left side of the unit. The construction is otherwise the same as the form shown in Figs. 1 to 3, 65 except for an alternate form of fuel burning stoker. In the modified unit, a horizontally arranged perforated plate grate 10 receives solid fuel from the fuel feeding mechanism 35. The space below the grate is divided by a longitudinal 70 vertical partition 71 into side-by-side air or blast chambers 72 into which depend air tubes 73 communicating with the tuyères or grate openings. The chamber 72 receives a supply of air from an external forced draft fan (not shown) through a 75

transverse duct 74 in the bottom part of the bridge wall 41 and separate inlet openings 75 controlled by dampers 76. The air becomes pre-heated during its passage through the bridge wall duct, air chamber tubes and tuyères, and passes upwardly into the fuel bed on the grate in a multiplicity of small jets. The operation otherwise is the same as in the construction shown in Figs. 1 to 3.

10 In Fig. 7 I have illustrated a four-drum boiler unit of the type disclosed and claimed in my said prior application. The steam generating water tube surface is mainly concentrated in two spaced vertical banks 25 and 25' respectively connected to upper and lower drums 23, 24 and 23', 24'. The furnace chamber in this form has its opposite sides and roof partly defined by oppositely arranged rows of L-shaped tubes 50' having their upper ends connected to the adjacent upper drum 23 or 23'. The fuel burning provisions shown in Figs. 4 to 6 are incorporated in the modification shown in Fig. 7 as well as the bridge wall and partition elements thereof. In Fig. 7 the heating gases generated divide at the rear end of the boiler between the two heating lanes at opposite sides thereof.

15 The steam boiler constructions illustrated are especially adapted for the low capacity field heretofore substantially monopolized by horizontal return tubular boilers. Although incorporating many features of modern central station design contributing to a high boiler efficiency, they can be manufactured at a cost but little, if any, greater than prior generating equipment used in 20 this field and may be installed in small spaces per unit of capacity.

25 While in accordance with the provisions of the statutes I have illustrated and described herein the best forms of my invention now known to me, 40 those skilled in the art will understand that changes may be made in the form of the apparatus disclosed without departing from the spirit of the invention covered by my claims, and that certain features of my invention may sometimes 45 be used to advantage without a corresponding use of other features.

I claim:

1. A steam boiler having upper and lower drums, a bank of vertically disposed water tubes 50 extending between and connected to said drums, means forming a longitudinally extending combustion lane and a heating lane laterally adjoining said combustion lane and containing said tube bank and communicating with said combustion lane at one end thereof, a stoker at the opposite end of said combustion lane for burning solid fuel thereon and generating heating gases flowing longitudinally through said combustion lane and thence through said heating lane, and 55 a dividing wall structure including transversely spaced refractory winged walls arranged to provide a restricted outlet for the heating gases to the remaining portion of said combustion lane.

2. A steam boiler having upper and lower drums, a bank of vertically disposed water tubes 60 extending between and connected to said drums, means forming a longitudinally extending combustion lane and a heating lane laterally adjoining said combustion lane and containing said tube bank and communicating with said combustion lane at the rear end thereof, a stoker at the front end of said combustion lane for burning solid fuel thereon and generating heating gases flowing rearwardly through said combustion lane and thence through said heating lane,

65 and a dividing wall structure at the rear of said stoker including transversely spaced refractory wing walls and a connecting arch constructed to provide a restricted outlet for the heating gases to the rear portion of said combustion lane. 70

3. A steam boiler having upper and lower drums, a bank of vertically disposed water tubes 75 extending between and connected to said drums, means forming a longitudinally extending combustion lane and a heating lane laterally adjoining said combustion lane and containing said tube bank and communicating with said combustion lane at the rear end thereof, a stoker at the front end of said combustion lane for burning solid fuel thereon and generating heating gases flowing rearwardly through said combustion lane and thence through said heating lane, and a dividing wall structure at the rear of said stoker including a bridge wall, spaced wing walls and an arch arranged to provide a central restricted outlet for the heating gases to the rear portion of said combustion lane. 80

4. A steam boiler having upper and lower drums, a bank of vertically disposed water tubes 85 extending between and connected to said drums, means forming a longitudinally extending combustion lane and a heating lane laterally adjoining said combustion lane and containing said tube bank and communicating with said combustion lane at the rear end thereof, a stoker at the front end of said combustion lane for burning solid fuel thereon and generating heating gases flowing rearwardly through said combustion lane and thence through said heating lane, and a row of L-shaped water tubes extending upwardly along the inner side of said stoker and across the upper portion of said combustion lane and having their upper ends connected to 90 said upper drum.

5. A steam boiler having upper and lower 40 drums, a bank of vertically disposed water tubes extending between and connected to said drums, means forming a longitudinally extending combustion lane and a heating lane laterally adjoining said combustion lane and containing said 45 tube bank and communicating with said combustion lane at the rear end thereof, a stoker at the front end of said combustion lane for burning solid fuel thereon and generating heating gases flowing rearwardly through said combustion lane 50 and thence through said heating lane, a dividing wall structure at the rear end of said stoker constructed to provide a restricted outlet for the heating gases to the rear portion of said combustion lane, a row of L-shaped water tubes extending upwardly along the inner side of and across the upper portion of the front end of said combustion lane, a longitudinal header connected to said L-shaped tubes, and a row of roof tubes 55 connecting said header to said upper drum. 60

6. A steam boiler having upper and lower drums, a bank of vertically disposed water tubes 65 extending between and connected to said drums, means forming a longitudinally extending combustion lane and a heating lane laterally adjoining said combustion lane and containing said tube bank and communicating with said combustion lane at the rear end thereof, said means including a vertically disposed longitudinally extending partition separating said combustion and heating lanes and arranged to form a forwardly tapering heating lane, means for burning fuel in said combustion lane and generating heating gases flowing serially through said combustion lane. 70

tion and heating lanes, and a heating gas outlet at the front end of said heating lane.

7. A steam boiler having upper and lower drums, a bank of vertically disposed water tubes extending between and connected to said drums, means forming a longitudinally extending combustion lane and a heating lane laterally adjoining said combustion lane and containing said tube bank and communicating with said combustion lane at the rear end thereof, said means including a vertically disposed longitudinally extending partition separating said combustion and heating lanes and having a rear section laterally offset relative to the forward section to form a forwardly tapering heating lane, means at the front end of said combustion lane for burning fuel and generating heating gases flowing rearwardly through said combustion lane and thence through said heating lane, and a heating gas outlet at the front end of said heating lane.

8. A steam boiler having upper and lower drums, a bank of vertically disposed water tubes extending between and connected to said drums, means forming a longitudinally extending combustion lane and a heating lane laterally adjoining said combustion lane and containing said tube bank and communicating with said combustion lane at the rear end thereof, means for burning fuel in said combustion lane and generating heating gases flowing serially through said combustion and heating lanes, a heating gas outlet at the front end of said heating lane, and vertically adjustable baffle means arranged to effect a downward flow of the heating gases adjacent said outlet.

9. A steam boiler having upper and lower drums, a bank of vertically disposed water tubes extending between and connected to said drums, means forming a longitudinally extending combustion lane and a heating lane laterally adjoining said combustion lane and containing said tube bank and communicating with said combustion lane at the rear end thereof, said means including a vertically disposed longitudinally extending partition separating said combustion and heating lanes and arranged to form a forwardly

tapering heating lane, means at the front end of said combustion lane for burning fuel and generating heating gases flowing rearwardly through said combustion lane and thence through said heating lane, a heating gas outlet at the front end of said heating lane, and vertically adjustable baffle means arranged to effect a downward flow of the heating gases adjacent said outlet.

10. A steam boiler having upper and lower drums, a bank of vertically disposed water tubes extending between and connected to said drums, means forming a longitudinally extending combustion lane and a heating lane laterally adjoining said combustion lane and containing said tube bank and communicating with said combustion lane, a stoker at one end of said combustion lane for burning solid fuel thereon and generating heating gases flowing longitudinally through said combustion lane and thence through said heating lane, a bridge wall structure at one end of said stoker constructed to provide a restricted outlet for the heating gases to the remaining portion of said combustion lane, separate air chambers below said stoker, a transverse passage through said bridge wall, and damper-controlled openings separately connecting said bridge wall passage to said air chamber.

11. A steam boiler having laterally spaced pairs of upper and lower drums, a bank of vertically disposed water tubes extending between and connected to each pair of said drums, means forming a longitudinally extending central combustion lane and a pair of heating lanes laterally adjoining and at opposite sides of said combustion lane, each heating lane containing one of said tube banks and communicating with said combustion lane at the rear end thereof, a stoker at the front end of said combustion lane for burning solid fuel thereon and generating heating gases flowing rearwardly through said combustion lane and thence through said heating lanes, and a dividing wall structure at the rear end of said stoker constructed to provide a restricted outlet for the heating gases to the rear portion of said combustion lane.

KARL C. SCHMIDT.
